UNITED STATES PATENT OFFICE.

SAMUEL K. APPLEBAUM, OF HOLLYWOOD, CALIFORNIA.

DESIGN FOR A BOTTLE.

Application filed August 21, 1928. Serial No. 27,903. Term of patent 14 years.

To all whom it may concern:

Be it known that I, SAMUEL K. APPLEBAUM, a citizen of the United States, residing at Hollywood, in the county of Los Angeles and State of California, have invented a new, original, and ornamental Design for Bottles, of which the following is a specification, reference being had to the accompanying drawing, forming part thereof.

Fig. 2 is a top plan view of the bottle.

I claim:

The ornamental design for a bottle, as shown.

SAMUEL K. APPLEBAUM.
